UNITED STATES PATENT OFFICE

130,994

DESIGN FOR A DOLL

Cora MacGeachy, Hollywood, Calif.

Application October 9, 1941, Serial No. 103,695

Term of patent 3½ years

To all whom it may concern:

Be it known that I, Cora MacGeachy, a citizen of the United States, residing at Hollywood, county of Los Angeles, and State of California, have invented a new, original, and ornamental Design for a Doll, of which the following is a specification, reference being had to the accompanying drawing, forming part thereof, wherein—

Fig. 1 is a front view of a doll showing my new design.

Fig. 2 is a side view thereof.

I claim:

The ornamental design for a doll, substantially as shown.

CORA MACGEACHY.
